US0D1111049S

(12) **United States Design Patent** (10) Patent No.: **US D1,111,049 S**
(45) Date of Patent: ** Feb. 3, 2026

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Karelys Alfonzo**, Coopersburg, PA
(US); **Rhodes B. Baker**, Bethlehem, PA
(US); **John H. Bull**, Coplay, PA (US);
Erica L. Clymer, Northampton, PA
(US); **Sanjeev Kumar**, Harleysville, PA
(US); **Aaron Peters**, Allentown, PA
(US); **Rahul Subramany**, Hellertown,
PA (US); **Shannon M. Sullivan**,
Coopersburg, PA (US)

(73) Assignee: **Lutron Technology Company LLC**,
Coopersburg, PA (US)

(**) Term: **15 Years**

(21) Appl. No.: **29/858,382**

(22) Filed: **Oct. 31, 2022**

Related U.S. Application Data

(63) Continuation of application No. 29/804,722, filed on Aug. 23, 2021, now Pat. No. Des. 969,857, which is a continuation of application No. 29/647,719, filed on May 15, 2018, now Pat. No. Des. 931,322, which is a continuation of application No. 29/562,239, filed on Apr. 24, 2016, now Pat. No. Des. 820,862.

(57) **CLAIM**

The ornamental design for a display screen or portion thereof with graphical user interface as shown and described.

DESCRIPTION

The patent or application file contains at least one drawing executed in color. Copies of this patent or patent application publication with color drawing(s) will be provided by the Office upon request and payment of the necessary fee.

The sole FIGURE shows a display screen or portion thereof with graphical user interface showing our new design.

The peripheral dashed broken lines illustrate a display screen or portion thereof and form no part of the claimed design. The interior broken lines illustrate portions of the graphical user interface which form no part of the claimed design.
